ILLUMINABLE JACK

William L. Paulson, Centerville, S. Dak.

Application April 28, 1953, Serial No. 24,725

Term of patent 14 years

(Cl. D41—1)

FIG. 1

To all whom it may concern:

Be it known that I, William L. Paulson, a citizen of the United States of America, residing at Centerville, State of South Dakota, have invented a new, original, and ornamental Design for an Illuminable Jack, of which the following is a specification, reference being had to the accompanying drawings, forming a part hereof.

I claim:

The ornamental design for an illuminable jack, as shown.
